UNITED STATES PATENT OFFICE.

PARSONS SHAW, OF MANCHESTER, COUNTY OF LANCASTER, ENGLAND.

DENTAL ENGINE.

SPECIFICATION forming part of Letters Patent No. 249,111, dated November 1, 1881.

Application filed June 7, 1881. (Model.) Patented in England January 3, 1881.

To all whom it may concern:

Be it known that I, PARSONS SHAW, of Manchester, in the county of Lancaster, England, have invented certain new and useful Improvements in Dental Engines, (for which I have obtained a Patent in Great Britain, No. 20, bearing date January 3, 1881;) and I hereby declare the following to be a full, clear, and exact description thereof, reference being had to the annexed drawings, forming part of this specification.

The main object of the invention is to improve the universal joint employed in dental engines by a hinge movement which will allow the swinging arm to play freely in any direction without straining the spiral transmitter or causing it to bind or buckle. This I accomplish by using bifurcations on the bearings and bending their ends at right angles to the bearings, then connecting these ends by pivots, all as hereinafter described.

The mechanism employed by me in performing my invention is illustrated in the accompanying drawings.

Figure 1 is an elevation of the entire machine. Fig. 2 is a side view of my improved universal joint. Fig. 3 is another view of the same. Fig. 4 is a plan of the same when straightened; and Fig. 5 shows my improved chuck.

Similar letters refer to similar parts in the different views.

I make use of a vertical tubular standard, *a*, the base of which I fit on a tripod or other stand, *b*, to which the treadle *c* is connected. I mount the driving-wheel *d* on the side of the standard, and near the floor, by preference, to insure steadiness. On the upper part of the standard *a* I mount a horizontally-swinging crane, which consists of a rod, *f*, a driven shaft, *g*, a stay, *j*, a bearing, *e*, mounted on the top of the rod *f*, and two bearings, *i* and *1*, at the end of the stay *j*. The rod *f* slides in a telescope-tube in the standard *a*, and the rod and the movable bearing *1* at the bottom of the stay *j* allow the crane to freely rotate. One end of the shaft *g* revolves in the bearing *e*, and outside the bearing the shaft is attached to the pulley *h*, which has two or more grooves of different sizes. The pulleys receive motion by a band from the driving-wheel *d*. The other end

of the shaft *g* is attached to a spiral transmitter, *s*, carried by my improved double-forked universal joint, to be described. By this spiral transmitter motion is imparted to a loose swinging arm or second shaft, *k*. This shaft 55 imparts motion, through another spiral transmitter inclosed in the sheath *n*, to a shaft in the hand-piece *o*, on which the instrument to be used is fastened, as hereinafter described.

I make use of a collar with a set-screw, *2*, on the rod *f*, and a collar with a set-screw, *3*, on the standard *a* below the bearing *1* on the stay *j*, which serve the purpose of raising and lowering the swinging crane and adjusting it in proper position.

Fig. 2 is a side view of my improved universal joint when the engine is at rest and the arm *k* is at right angles to the arm *g*. Fig. 3 is a side view of the same when bent double and the two shafts *g* and *k* are parallel to each other. Fig. 4 is a plan of the same when seen from the top and when straightened so that the shafts *g* and *k* and the transmitter *s* are in a continuous line.

My universal joint consists of a double-sleeve 75 fork-joint and couplings. In each part or joint of the couplings there is a cylinder or sleeve *m* and *r*, which form bearings to the shafts *g* and *k*. From the cylindrical part of the couplings extend two forks, *4* and *5*, which end in 80 right-angle projections. These projections are connected together at the ends *t* by means of pins, which form a hinge and allow them to move freely on one another. Between these forks runs the transmitter *s*, which is fastened 85 to the shafts *g* and *k* by means of nuts, into which the shafts are screwed. These nuts form collars to keep the shafts in the bearings *m* and *r*, and the one attached to the shaft *g* holds the first part of the universal joint in its bearing *i*.

The transmitter *s* is protected from injury and prevented from buckling by means of a spiral sheath, *l*, fitted at each end on cylindrical projections from the sleeves *m* and *r*, and is itself protected by the sides of the forks *4* and *5*, between which it is placed. On the forks *4* and *5* are arranged stops *6* to prevent the couplings from bending except on the sides from which the right-angle projection of the 100

forks arise. By preference, the stop prevents the joint from becoming quite straight, so as to prevent it turning round with the transmitter.

- The change in the length of the transmitter 5 *s*, as it is straight or curved, is compensated by allowing the shaft *g* a little play on the bearing *e* and a little play to the shaft *k* in its bearing on the sleeve *r*. The cylindrical or sleeve part *m* of the first joint always remains o in a line with the shaft *g*, and rotates freely in the bearing *i* attached to the stay *j*, and this gives one of the motions of the universal joint. The other is got by the transmitter *s*, which runs freely either straight or bent, protected 5 by the spiral shaft *l* and the novel right-angle termination of the forks 4 and 5, connected by the hinge *t*, by which the transmitter, however much or little it is bent, is always maintained in a simple curve.
- o Fig. 5 shows a hand-piece in section, in which runs a short shaft at the end of which is the chuck *p*, which is slightly tapered inside, and when the end of the implement, which is tapered to correspond, is pressed in it is held firmly. I thus dispense with the use of springs or screws and other devices for holding the implement.

I am aware that the shaft and its connected arm or section have been connected with the opposite ends of a wire coil, and that the forks 30 or yokes have been jointed, but not bent at the ends.

What I claim as new and of my invention is—

1. In a dental engine, the combination, with 35 the drive-shaft *g*, transmitter *s*, and swinging arm *k*, said shaft and arm being attached to opposite ends of the transmitter, of the forked sleeves *m r*, having their prongs end-bent at about a right angle and connected by a pivot, 40 as shown and described, whereby the arm *k* may be allowed free play without straining the transmitter or causing it to buckle.

2. In a dental engine, the stay *j*, provided with an adjustable collar at each end, in combination with the rods *a f*, the drive-shaft *g*, and the bearings *e i*, as and for the purpose specified.

PARSONS SHAW.
